UNITED STATES PATENT OFFICE

HOWARD JOHN FOUNTAIN, OF LONDON, ENGLAND, ASSIGNOR OF ONE-HALF TO THE
CLARKSON THIMBLE TUBE BOILER COMPANY, OF LONDON, ENGLAND

STEAM GENERATOR OR WATER HEATER

Application filed April 16, 1929, Serial No. 355,460, and in Great Britain February 14, 1928.

This invention relates to steam generators or water heaters of the kind comprising an annular water chamber having short tubes or thimbles projecting radially inwards into a central space through which the hot gases pass.

The invention has for its object to provide a simple and inexpensive construction of boiler of this kind which can be built up from stock parts and which permits of cheap renewal.

In accordance with the invention the inner wall of the boiler is built up of a plurality of cast iron units in the form of annuli with thimbles projecting radially inwards, the said units being superposed and fitting direct one upon the other and being surrounded by an outer shell whereby to define with the outer shell the annular water chamber of the boiler. The upper and lower edges or faces of the units may be machined to form flat joint faces or one face of each unit may be formed with a circular rabbet or groove or the like and the opposite face may present a circular rib engageable with the rabbet in the adjacent unit whereby to form a joint. The rabbets or grooves and ribs may be tapered. The outer shell of the boiler may also be of cast metal and be adapted to fit within circular rabbets or grooves in suitably formed boiler end plates.

The superposed units may be held together by tie rods disposed externally of the outer shell, or the units may be held together by tie rods located in the water chamber and extending between the upper and lower end plates, said tie rods being screwed into the lower end plate and projecting through the upper end plate for engagement by nuts associated with hard rubber washers ensuring joint tightness.

The combustion chamber and the base may be in two separate units. The base may be square and provided with a circular seat for the combustion chamber so that these members may occupy any suitable angular position with respect to one another.

The smoke-box may be secured by studs to the upper end plate while the stoking chute 50 may merely rest on the smoke-box.

The superposed units may be so disposed with respect to one another as to provide a staggered arrangement of the thimbles.

The invention is illustrated in the accompanying drawings in which Fig. 1 is a front elevation of a steam generator or water heater in accordance with the invention; Fig. 2 is a vertical section on the line A—B of Fig. 1; Figs. 3, 4 and 5 are detail views of the cast iron units; Fig. 6 is a horizontal section through the smoke-box substantially on the line C—D of Fig. 1.

As shown the boiler is built up of a plurality of cast metal units 1 in the form of annuli with thimbles 2 projecting radially inwards. The units are adapted to be superposed, the upper face of each unit being formed with a circular rabbet 3 or the like for engagement with the lower edge 4 of the superposed unit (see particularly Figs. 3—5) whereby to form joints between the units. The rabbets or grooves 3 and the mating edges 4 are correspondingly tapered. The outer shell 5, defining with the superposed units 1, the water chamber 6 of the boiler, may also be of cast metal, said shell being adapted to engage circular rabbets 7 in the end plates 8, 9 of the boiler.

Between the assembled thimbled units 1 and the end plates 8, 9 of the boiler are interposed short tubes or rings 10, 11, each machined on one edge to mate with the adjacent unit, the other edge of each ring being in engagement with a rabbet or groove 12 formed in the relative boiler end plate.

Hard rubber packing may be fitted into the rabbets 7, 12 in the end plates 8, 9 to form fluid tight joints.

The end plates 8, 9 are interconnected by the rods 13 located in the water chamber 6, said rods being screw-threaded into the lower end plate 9 and projecting through clearance holes in the upper end plate 8 for engagement by nuts 14. 15 denotes hard rubber washers interposed between the upper cover 8 and the tie rod nuts 14.

16 denotes the combustion chamber which is separate from the base 17, the base being formed with a circular seat 18 engaging the lower edge of the chamber 16, the construc-

tion being such that the members may occupy any suitable angular position with respect to one another. The base door 19 may be controlled by a thermostat (not shown).

5 20 denotes the smoke-box secured by studs to the upper end plate 8. The stoking chute 21 rests on top of the smoke box 20. A pet cock (not shown) may be provided on the cover 22 of the stoking chute 21 so that any 10 gas in the chute may be ignited and burnt before removal of the cover.

It will be understood that if units as described and outer shells of one or more different sizes be kept in stock the erection of a 15 boiler of any particular dimensions may be rapidly effected.

I claim:—

In a steam generator or water heater, an outer wall, an inner wall, end plates, means 20 for securing said outer and inner walls and end plates together to form an annular water space, said inner wall comprising a plurality of interfitting annuli, at least some of which have inwardly directed thimbles or spurs, 25 said thimbles terminating a distance from the center of the generator and defining a central passage, a coking chute extending downwardly through said central passage, the lower end of said chute terminating adjacent the lower edge of the lowermost annuli, and a filler ring between said lowermost annuli and the lower end plate.

30 In testimony whereof I have signed my name to this specification.

35 HOWARD JOHN FOUNTAIN.
